Primary Examiner—Jeffrey Asch**[57] CLAIM**

The ornamental design for a compact disc rack, as shown and described.

DESCRIPTION

FIG. 1 is a perspective view of a compact disk rack showing my new design;

FIG. 2 is a top plan view thereof;

FIG. 3 is a right side elevational thereof; the opposite side being identical;

FIG. 4 is a bottom view thereof;

FIG. 5 is front elevational view thereof;

FIG. 6 is a perspective view of a second embodiment of my invention for an ornamental design used for a compact disc rack;

FIG. 7 is a top plan view of FIG. 6;

FIG. 8 is a right side elevational thereof of FIG. 6; the opposite side being identical;

FIG. 9 is a bottom view of FIG. 6; and,

FIG. 10 is front elevational view of FIG. 6.
